UNITED STATES PATENT OFFICE

HARRY F. BENSON, OF HOLYOKE, MASSACHUSETTS, ASSIGNOR TO WORTHINGTON PUMP AND MACHINERY CORPORATION, OF NEW YORK, N. Y., A CORPORATION OF VIRGINIA

DEEP-WELL PUMP

Application filed March 27, 1929. Serial No. 350,174.

This invention relates to deep well pumps, and more particularly to a jacket pump structure for pumping cooling water into the cooling chamber of the driving heads of deep well pumps.

An object of the present invention is to provide a positive, dependable water cooling system for deep well pumps; particularly those having surface discharge, that is, where there is not sufficient excess head to throw the water up into the cooling chambers of the driving heads of the pumps; which is simple in construction, is rugged, dependable for use in deep well pump structures of either the plain cover pipe or tension cover pipe system, and one which can be used in connection with various approved oil lubricating systems without danger of mixing water and oil.

With these and other objects in view as may appear from the accompanying specification, the invention consists in various features of construction and combination of parts, which will be first described in connection with the accompanying drawings, showing a pump of the preferred form embodying the invention, and the features forming the invention will be specifically pointed out in the claims.

In the drawings:

Fig. 1 is a vertical section through the power end of a deep well pump, showing the improved cooling water structure applied thereto.

Fig. 2 is a detailed section through a part of the pump structure and taken on the line 2-2 of Fig. 1.

Fig. 3 is a side elevation partly in section, showing the cooling water pumping system applied to a slightly different type of deep well pump.

Referring more particularly to the drawings, the improved jacket pump for circulating cooling water is shown in Figs. 1 and 2 of the drawings as applied to an approved type of deep well pump embodying a motor 1, which drives the driving shaft 2 through a series of couplings and the thrust bearing structure 3, as is usual in this type of deep well pumps. The thrust bearing structure

3 is enclosed within a suitable housing 4, in which oil is placed, as shown at 5, and it is for the purpose of cooling this oil and the thrust bearing 3 that the improved cooling water circulating pump is provided. 55

The solid impeller driving shaft 2 of the pump is connected by the coupling 6 to the relatively short hollow connecting shaft 7; which shaft extends upwardly through the main stuffing box 8 and is connected by a suitable coupling 9 to the motor shaft 10. The hollow shaft 7 is provided with openings 11, which open into the lantern gland 12 in the stuffing box structure 8, and lubricating oil is admitted to the interior of the hollow shaft 7 through the openings 11 and lantern gland 12 from a suitable supply reservoir 13, through the suitable conduit 14, which may be a flexible tube if desired. The lubricating oil is pumped into the shaft 7 from the reservoir 13 by any suitable type of pump structure, as indicated at 15, and it flows downwardly through the hollow shaft and out of the shaft through the openings 16 into the spring space 17 in the casing 18 of the jacket pump. The casing 18 is threadably connected at its lower end to the cover pipe 19 of the pump structure and the lubricating oil, which flows into the spring space 17, flows past the follower 20 into the cover pipe 19 and it is prevented from flowing upwardly into the casing by the packing 21 of any approved type, which is packed or held tightly in position by the spring 22 in the spring space 17. When the cover pipe 19 is full of oil, the valve 23 may be adjusted for regulating the normal flow of oil into the cover pipe. 70 75

The oil chamber 4 of the thrust bearing 3 is surrounded by a cooling jacket 25 and cold water is circulated through this cooling jacket 25 by the jacket pump structure, which includes the casing 18 and the impeller 26. The impeller 26 is mounted on the lower end of a sleeve 27 which is carried by the hollow shaft 7. The casing 18 extends downwardly into the main discharge elbow 28 of the pump proper and it is provided with a plurality of openings 29, positioned so as to be below the normal water level in the elbow 100 90 95

28. The rotation of the impeller 26 of the jacket pump will force water, which enters the casing 18 through the openings 29 upwardly through the space 30 in the flange 31 and outwardly through the flexible pipe 32 into the water jacket 25. Water flows from the water jacket 25 through the outlet pipe 33, which may discharge at any suitable point or be connected to the discharge pipe of the pump, if it is so desired, without departing from the spirit of this invention.

As previously stated, the lower end of the casing 18 is threaded on to the top end of the cover pipe 19 and it is so made that by turning the flange 31 and the casing 18, the tension of the cover pipe may be regulated, or, in other words, the cover pipe may be put in tension if desired. The sleeve 27, which carries the impeller 26, is adjustable on a hollow shaft 7 and is held in adjusted position and for rotation with the shaft 7 by a set screw 35.

From the foregoing description, taken in conjunction with the accompanying drawings, it will be apparent that cooling water, for cooling the thrust bearing 3, will be efficiently supplied from the main discharge of the pump by means of the jacket pump structure including the impeller 26, and, also, that all liability of mixing of water with the oil in the cover pipe structure will be eliminated, as well as mixture of oil with the water, and that while the improved jacket pump is shown as used in connection with a deep well pump having a particular type of lubricating system, it is to be understood that it may be applied to any approved type of deep well pump having any approved type of lubricating system, and, also, that it may be employed with pumps other than those of what is known as the tension cover pipe type.

For example; in Fig. 3 of the drawings, the improved jacket water pump is shown employed in connection with a deep well pump structure 40 in which the shaft 41 is not hollow and the lubricating oil is supplied directly to the cover pipe 42 through a suitable connection 43 below the lower end of the casing 18' of the jacket water pump.

The flange 31 of the pump shown in Figs. 1 and 2 of the drawings, and the flange 31' of the pump shown in Fig. 3 of the drawings, may be provided with a plurality of circumferentially spaced openings 36 to permit connection of the flexible conduit 32 or 32' with the flanges at various points, it being understood that these openings are normally closed in any suitable manner.

It will also be noted from the foregoing description and the accompanying drawings, that the improved type of jacket water pump is specially adapted for use in deep well pumps of the type where the cover pipe is to be kept in tension and that it will at the same time make it possible to attach the impeller of the jacket water pump directly to the rotat-

ing shaft 7 low enough to operate below the discharge water level of the deep well pump proper, thereby needing no priming, and at the same time provide a complete separation of the oil system from the water, and, further, will allow the turning of the casing 18 to tighten the cover pipe 19, as desired or necessary.

It will be understood that the invention is not to be limited to the specific construction or arrangements of parts shown but that these may be modified widely within the invention defined by the claims.

What is claimed is:

1. The combination with a deep well pump embodying a driving shaft and a cover pipe therefor, of a cooling water circulating pump including an impeller carried by said shaft, and a casing for said impeller threaded to said cover pipe whereby the tension of the cover pipe may be varied by adjustment of the casing.

2. The combination of a deep well pump embodying a driving shaft, a thrust bearing therefor, a cover pipe about a part of the driving shaft, a cooling water pumping impeller carried by said shaft for circulating cooling water about said thrust bearing, a casing for said impeller, said casing being threaded to said cover pipe whereby the tension of the cover pipe may be varied by adjustment of the casing.

3. The combination of a deep well pump embodying a driving shaft, a cover pipe therefor, and a power end housing, of a water jacket carried by the housing, a cooling water circulating pump including an impeller carried by said shaft for circulating cooling water through said housing and a casing for said impeller carried by the housing and extending below the discharge level of the deep well pump, said casing being threaded to said cover pipe whereby the tension of the cover pipe may be varied by adjustment of the casing.

4. The combination with a deep well pump embodying a driving shaft, a cover pipe therefor, of a cooling water circulating pump including an impeller carried by said shaft, a casing for said impeller, means for supplying lubricating oil to said cover pipe, and fluid tight packing carried by said casing for preventing mixing of the water and lubricating oil.

In testimony whereof I affix my signature.

HARRY F. BENSON.
